EARRING OR THE LIKE

La Vesta Lee Garber, Chicago, Ill.

Application February 21, 1955, Serial No. 34,622

Term of patent 7 years

(Cl. D45—9)

Fig. 3

Fig. 1

Fig. 2 is a side elevation thereof; and

Fig. 3 is a top plan view thereof.

The dominant features of my design reside in the portions shown in full lines.

I claim:

The ornamental design for an earring or the like, as shown and described.
